CUT-OFF AND TRANSFER MECHANISM

Richard Lester Wilcox, Waterbury, Conn., assignor to The Waterbury Farrel Foundry and Machine Company, Waterbury, Conn., a corporation of Connecticut

Application January 6, 1937, Serial No. 119,240

23 Claims. (Cl. 10—25)

This invention relates to new and improved cut-off mechanism of the type particularly adapted for upsetting, heading machines, or the like.

In machines of the character indicated a rod 5 length or a coil of wire, herein referred to as a rod, is fed through a cut-off die, or the like, a predetermined distance. That portion of the rod projecting beyond the cut-off die is severed therefrom on a line coincident with the face of the 10 cut-off die and then becomes a blank. The blank is then transferred from its position in line with the cut-off die to one wherein its axis is substantially coincident with that of an adjacent die. From this position it is projected into the die 15 and an operation performed thereon.

The improved mechanism herein described relates particularly to devices for cutting off a portion of the rod and carrying it to another die or dies.

It is essential in some classes of work that the 20 cut-off end of the blank should be square with the length thereof, that is, at a right angle thereto.

An object of this invention is to provide mechanism that will so sever the blank from the rod that the end thereof will be at a right angle to its 25 length and transfer it from its cut-off position to a succeeding die or station for operations thereon.

Other objects and novel features of the invention will appear from the description of the invention as herein set forth and illustrated in the drawings, wherein like numerals of reference indicate like parts in the several figures;

Figure 1 is a fragmentary elevation of a portion 35 of an upsetting, heading machine, or the like, and of the cut-off and transfer mechanism described herein, shown in its relative position at substantially the beginning of its forward or cut-off and transfer movement;

Figure 2 is a fragmentary plan view of the 40 parts, substantially as shown in Figure 1;

Figure 3 is a view similar to Figure 1, with the 45 cut-off and transfer mechanism shown in the position as it engages the rod at the beginning of the cut-off or shearing operation;

Figure 4 is a similar view with the cut-off mechanism shown as it begins its return movement to its cut-off position after presenting the blank to the first die beyond the cut-off die;

Figure 5 is a perspective view of the cut-off 50 and transfer mechanism and a portion of the carrier;

Figure 6 is a transverse sectional view of some 55 of the parts taken generally upon line 6—6 of Figure 3; and

Figure 7 is a transverse sectional view of some of the parts taken generally upon line 7—7 of Figure 3.

Referring to the drawings, 10 indicates the body of a header, upsetting machine or the like, in which is fixed a die block 11, carrying plural dies, that is, a cut-off die 12 and a fabricating die 13.

In the drawings only two of these dies are shown, but the number thereof may be increased 10 as seems desirable or may be necessary.

Through the cut-off die a rod 14 is intermittently fed by any suitable means well known in the art.

It is customary that the inward limit of the 15 movement of this intermittent fed should be determined by adjustable mechanism, such as a stop device, or the like, not shown, but well known.

The above described mechanism is old and well known and constitutes no part of the present invention.

Actuated by mechanism well known in the art, so as to derive a reciprocatory movement within a bushing 16, or the like, is a carrier 15. The inner end of this carrier is shaped so as to provide a substantially flat face 17 terminating at its inner end in an angular wall 18. While the carrier 15 is shown as moving in a substantially straight path, it may within the spirit and scope of this invention move in a curved or other path.

The numeral 19 indicates the knife holder, 30 which has a tail piece 20, one wall of which rests against the face 17 with the rear end thereof abutting against the angular wall 18. This knife holder 19 is separably secured to the carrier by the screw 21, or the like which passes through the carrier and is threaded into the tail piece, substantially as shown in Figure 6.

In the inner wall of the knife holder 19 is a recess, within which is secured, by a screw 22, 40 or the like, the fixed knife 23, the forward end of which projects beyond the knife holder. Journaled on a stud 24 adjacent to the outer wall of the knife holder is the carrier member 25, having a tail piece 26. Secured to this carrier member 25 by the screw 27, or the like, is the movable knife 28.

To insure the maintenance of the fixed relation of the carrier member 25 and movable knife 28 a recess is provided in the adjacent face of each, so that the parts may interlock, substantially as shown in Figures 2 and 5. A spring 29 exerts its pressure so as to hold the movable knife 28 in its down position with its lower edge in contact with the knife 23. The upper outer face 45 50 55 55

of the knife 23 is cut away at 30, substantially as shown in Figure 4, the inner end 31 of which is curved with a radius substantially the same as that of the rod.

5 The lower face of the movable knife 28 has a curved opening 32 therein, the radius of which is substantially the same as that of the rod, so that when the knives are in substantially the position shown in Figures 3 and 5 they surround the rod approximately 270° and grip the same for the 10 major portion of its circumference.

As the surface of the cut away portion 30 is in substantially the same plane as the underside of the blank, it provides support therefor during 15 the first portion of the return movement of the carrier and while the blank is being projected into the die 13.

For rods of different diameters new knives having openings therein to correspond in diameter 20 with that of the rod may be substituted.

The rear face 33 of the movable knife 28 when in its down position engages a wall on the fixed knife 23. One side of the movable knife 28 in its down position is in engagement with the lip 35 and on the other side is flush with and movable across the face of the cutter die 12 and the face of the die block 11 (Fig. 7). Thus, the movable knife 28 is held against lateral movement and there are no joints, bearings, or the like, to 30 wear, disturb or disarrange this assured rigid position relative to the rod and blank.

In operation the rod is projected through the cut-off die when the cut-off and transfer mechanism is in substantially its rearmost position, 35 as shown in Figure 1, at which time the movable knife 28 is in its open position. This open position results from the engagement by the tail piece 26 on the carrier member 25 with a face of the cam piece 37, which is adjustably secured 40 to the body 10 by screws 38 or the like.

Shortly after the inward movement of the carrier has begun, the tail piece 26 rides off the cam face and the spring 29 causes the movable knife 28 to swing to its down position and enclosing 45 the projecting portion of the rod 14. Its then position is substantially as shown in Figure 3. These knives jointly sever the projecting portion of the rod on the line coincident with the face of the cut-off die during the continued movement 50 of the carrier and the cut-off portion, now a blank, is carried into a position wherein the axis of the blank is coincident with the opening in the next succeeding die 13.

After the blank has been projected into the 55 die a sufficient distance to support it, the carrier begins its return movement and the movable knife 28, by reason of its flexible mounting, swings free over the blank and is returned and ready for another cut-off operation. During this return 60 movement the tail piece 26, on the carrier member 25, engages the cam face of the cam piece 37, actuates said carrier member and movable knife 28, and holds the same in its open position ready for its next forward stroke. Adjustment of 65 the relative position of the cam piece 37 insures a proper timing of the movement of the movable knife 28.

As the rod is gripped firmly by the knives parallel to its length and the latter must maintain 70 such relative position, irrespective of the strain that may be placed thereon by severing the rod, the sheared ends of the rod must necessarily be at a right angle to its length.

The rod cannot bend as it is sheared off, neither 75 can that portion thereof in front of the face of

the cut-off die be moved into an angular position relative to said face. That face of the movable knife 28 which is adjacent to the face of the die block 11 is relatively wide, and being held against lateral movement by the lip 35 and carrier member 25, a movement exactly parallel with the axis of the rod is assured, with the result that the cut is square rather than angular or otherwise. The inner face of the carrier member 25 is substantially parallel with the face of 10 the die block 11 and the adjacent wall of the knife holder 19. Thus the movable knife 28 is further held against any possible lateral motion while under labor. The fixed knife 23, being rigidly secured to the carrier 15, cannot possibly 15 have any lateral movement.

Numerous modifications, changes and rearrangements of the structure may be adopted within the scope of the appended claims.

I claim:

1. In mechanism of the character described, wherein a rod is advanced through a cut-off die; a carrier or the like; and plural knives mounted on the carrier to sever a portion of the rod, one knife fixedly and the other movably.

2. In mechanism of the character described, wherein a rod is advanced through a cut-off die; a carrier or the like; and plural knives to sever a portion of the rod, one knife being fixed and the other movable in relation to the carrier and 30 toward and away from the fixed knife, the opposing faces of these knives when substantially in contact with each other almost completely surrounding the rod.

3. In mechanism of the character described, wherein a rod is advanced through a cut-off die; a carrier or the like; and plural knives mounted on the carrier to sever a portion of the rod, one knife fixedly and the other movably, the movable knife being so positioned that one face thereof 40 is adjacent to the face of the cut-off die and the opposite face thereof adjacent to a part fixed to the carrier and whereby the knife is held against relative movement while under labor during the cut-off operation.

4. In mechanism of the character described, wherein a rod is advanced through a cut-off die; a carrier or the like; plural knives mounted on the carrier to sever a portion of the rod, one knife fixedly and the other movably; and means 50 for so mounting the movable knife that it is flanked upon opposite sides by non-yielding walls.

5. In mechanism of the character described, wherein a rod is advanced through a cut-off die; a carrier or the like; plural knives mounted on 55 the carrier to sever a portion of the rod, one knife fixedly and the other movably; and means for so mounting the movable knife that it is flanked upon opposite sides by non-yielding walls while the rod is being severed.

6. In mechanism of the character described, wherein a rod is advanced through a cut-off die; a carrier or the like; and plural knives mounted 60 on the carrier to sever a portion of the rod, one knife fixedly and the other movably, the movable knife during the severing operation having contact with four non-yielding walls.

7. In mechanism of the character described, wherein a rod is advanced through a cut-off die; a carrier or the like; and plural knives mounted 70 on the carrier to sever a portion of the rod, one knife fixedly and the other movably, one of said knives having an opening in one edge thereof substantially the same as approximately one-half of the periphery of the rod, and the other 75

knife having a cutaway portion, the inner end of which is substantially the same shape as approximately one-quarter of said periphery.

8. In mechanism of the character described, 5 wherein a rod is advanced through a cut-off die; a carrier or the like; plural knives to sever a portion of the rod, one knife being fixed and the other movable in relation to the carrier; and yielding means that exerts its tension to move 10 and maintain the movable knife to its position in engagement with the fixed knife.

9. In mechanism of the character described, wherein a rod is advanced through a cut-off die; a carrier or the like; plural knives to sever a 15 portion of the rod, one knife being fixed and the other movable in relation to the carrier; a carrier member; and means for securing the movable knife to the carrier member, whereby the movable knife will be caused to travel toward and 20 away from the fixed knife in part by the carrier member.

10. In mechanism of the character described, wherein a rod is advanced through a cut-off die; a carrier or the like; plural knives to sever a 25 portion of the rod, one knife being fixed and the other movable in relation to the carrier; a carrier member; means for securing the movable knife to the carrier member, whereby the movable knife will be caused to travel toward and away 30 from the fixed knife in part by the carrier member; and means for positively actuating the carrier member during a portion of the movement of the carrier.

11. In mechanism of the character described, 35 wherein a rod is advanced through a cut-off die; a carrier or the like; plural knives to sever a portion of the rod, one knife being fixed and the other movable in relation to the carrier; a carrier member; means for securing the movable 40 knife to the carrier member, whereby the movable knife will be caused to travel toward and away from the fixed knife in part by the carrier member; and means, as a cam or the like, for positively actuating the carrier member during 45 a portion of the movement of the carrier.

12. In mechanism of the character described, wherein a rod is advanced through a cut-off die; a carrier or the like; plural knives to sever a 50 portion of the rod, one knife being fixed and the other movable in relation to the carrier; a carrier member; means for securing the movable knife to the carrier member, whereby the movable knife will be caused to travel toward and away from the fixed knife in part by the carrier member; and a member in the path of the carrier member, whereby during the movement of the carrier the carrier member is in engagement with the member and actuated thereby.

13. In mechanism of the character described, 60 wherein a rod is advanced through a cut-off die; a die block; a cut-off die mounted therein, the face being substantially flush with that of the die; a carrier or the like; plural knives mounted on the carrier to sever a portion of the rod during 65 the movement of the carrier, one knife being fixed and the other movably; a carrier member having the movable knife connected therewith; and means for mounting said carrier member, whereby one face thereof is substantially parallel with 70 that of the face of the die block.

14. In mechanism of the character described, 75 wherein a rod is advanced through a cut-off die; a carrier or the like; plural knives to sever a portion of the rod, one knife being fixed and the other movable in relation to the carrier; a car-

rier member; means for securing the movable knife to the carrier member, whereby the movable knife will be caused to travel toward and away from the fixed knife in part by the carrier member; a cam in the path of the carrier member, whereby during the movement of the carrier the carrier member is in engagement with the cam and actuated thereby; and yielding means resisting the action of the movable knife when the same is actuated through the carrier member. 10

15. In mechanism of the character described, wherein a rod is advanced through a cut-off die; a die block; a cut-off die in said die block; a fabricating die in said die block; a carrier or the like; plural knives to sever a portion of the rod, one knife being fixed and the other movable in relation to the carrier; and means for mounting the movable knife, whereby it will co-operate with the fixed knife to sever that portion of the 20 rod projecting through the cut-off die and hold such portion during the further movement of the carrier and present the same in line with the fabricating die.

16. In mechanism of the character described; 25 a carrier; a knife holder secured thereto; a carrier member mounted on the knife holder; a fixed knife secured to the knife holder; and a movable knife secured to the carrier member.

17. In mechanism of the character described, 30 wherein a rod is advanced through a cut-off die; a die block; a cut-off die mounted therein, the face being substantially flush with that of the die block; a carrier or the like; a knife holder with a forwardly projecting lip fixed to the carrier and having one face substantially parallel with the face of the die holder; a carrier member on the knife holder; a knife fixed to the knife holder and projecting in advance of said lip; and a movable knife fixed to the carrier member with 40 one face thereof adjacent to the inner face of said lip.

18. In mechanism of the character described, wherein a rod is advanced through a cut-off die; a carrier or the like; plural knives to sever a 45 portion of the rod, one knife being fixed and the other movable in relation to the carrier; a carrier member with which the movable knife has an interlocking connection; and means for separably securing the knife to the carrier member, whereby the movable knife will be caused to travel toward and away from the fixed knife in part by the carrier member.

19. In mechanism of the character described, 55 wherein a rod is advanced through a cut-off die; a die block; a cut-off die in said die block; a fabricating die in said die block; a carrier or the like; plural knives to sever a portion of the rod, one knife being fixed and the other movable in relation to the carrier; and means for mounting the movable knife, whereby it will co-operate with the fixed knife to sever that portion of the rod projecting through the cut-off die and hold such portion during the further movement of the carrier and present the same in line with the 60 fabricating die, the movable knife lifting from the blank after the same has been in part projected into the fabricating die and during the 65 first portion of the return movement of the carrier.

20. In mechanism of the character described, 70 wherein a rod is advanced through a cut-off die; a die block; a cut-off die in said die block; a fabricating die in said die block; a carrier or the like; plural knives to sever a portion of the 75

rod, one knife being fixed and the other movable in relation to the carrier; and means for mounting the movable knife, whereby it will co-operate with the fixed knife to sever that portion of the rod projecting through the cut-off die and hold such portion during the further movement of the carrier and present the same in line with the fabricating die, during the return movement of the carrier, the movable knife moving upon its pivot mounting and being disengaged from the blank as it is projected in the fabricating die, at which time the substantially straight wall of the cutaway portion of the fixed knife supports the blank upon the underside thereof.

21. In mechanism of the character described, wherein a portion of a rod is severed at a cut-off die or the like; a carrier or the like; and plural knives mounted on the carrier to sever such rod portion, one knife fixedly and the other movably, the movable knife during the severing operation having contact with a plurality of non-yielding walls.

22. In mechanism of the character described,

wherein a portion of a rod is severed from the rod at a cut-off die or the like, and such portion transferred to and projected into a fabricating die or the like; a carrier; plural knives mounted on the carrier to sever said portion and carry it to the fabricating die, one knife supporting said portion in part while being projected into the die; and means for moving one of said knives to its open position during the withdrawal movement of the cutter and maintaining such position until it is closed at the next forward movement of the carrier.

23. In mechanism of the character described, wherein a portion of a rod is severed from the rod at a cut-off die or the like, and such portion transferred to and projected into a fabricating die or the like; a carrier; a cutter having plural knives on the carrier to sever said portion and carry it to the fabricating die, and means for moving one of said knives to its open position during the withdrawal movement of the cutter and maintaining such position until it is closed at the next forward movement of the carrier.

RICHARD LESTER WILCOX.
